ROOF COVERING OR SIMILAR ARTICLE

Robert F. Green, Westfield, N.J., assignor to Johns-Manville Corporation, New York, N.Y.

Filed Nov. 12, 1969, Ser. No. 20,050

Term of patent 14 years

Int. Cl. D25—01

U.S. Cl. D68—1

FIG. 1 is a plan view of a roof covering showing my new design; and

FIG. 2 is a plan view of a modification of the roof covering shown in FIG. 1.

I claim:

The ornamental design for a roof covering or similar article, as shown and described.
